UNITED STATES PATENT OFFICE.

CHARLES G. KRAMER, OF CHICAGO, ILLINOIS, ASSIGNOR TO THE UNION SPECIAL SEWING MACHINE COMPANY, OF CHICAGO, ILLINOIS, A CORPORATION OF ILLINOIS.

SEWING-MACHINE.

No. 885,624.

Specification of Letters Patent. Patented April 21, 1908.

Application filed April 26, 1899. Serial No. 714,555.

To all whom it may concern:

Be it known that I, CHARLES G. KRAMER, a citizen of the United States, residing at Chicago, in the county of Cook and State of Illinois, have invented certain new and useful Improvements in Sewing-Machines, of which the following is a description, reference being had to the accompanying drawing and to the letters and figures of reference marked 10 thereon.

My invention relates to an improvement in sewing machines, the object being especially to provide a machine of the chain stitch type, which is capable of greater adjustment than 15 those heretofore used.

The ordinary double chain stitch sewing machine of the Union Special type is, as is well known, provided with an oscillating bar upon which is supported a looper rocker having 20 in its upper part a socket in which the shank of the looper is secured.

It has been heretofore proposed to provide more than one socket whereby a plurality of loopers may be arranged on the same rocker 25 but in such an arrangement of a single rocker, of course, the capability of adjustment of the machine to accommodate different gages or different widths of seams is more or less limited.

30 The present invention is designed for increased adjustment to adapt it for almost any gage seam and primarily consists in providing upon the looper supporting shaft or bar a plurality of looper rockers, all actuated from the same source and correspondingly timed and by increasing the number of rockers as well as the number of loopers upon the rockers very many rows of stitches may be sewed at the same time, and a seam of maximum width be made.

In the accompanying drawings, Figure 1 is a side elevation of so much of a sewing machine of the well known Union Special type as is necessary to a complete understanding 45 of the invention, Fig. 2 is a top plan view of the front portion of the machine, the goose neck and bed plate being removed; Fig. 3 is a perspective view enlarged of the forward part of the machine, the feeding mechanism 50 being omitted; Fig. 4 is a detail view of the looper rocker supporting shaft or arm detached; Fig. 5 is a detail view of one of the looper rockers looking towards the heel of the looper; and Fig. 6 is a view similar to Fig. 4

showing an arrangement whereby the rockers 55 may be adjusted.

In these drawings, A represents as a whole a Union Special sewing machine of the type illustrated in Patent #299,568, of June 3, 1884, granted to Muther & Dearborn. In 60 the present instance, the invention is shown as applied to a machine having a very wide presser foot 1, with two adjustable needles arranged diagonally to each other respecting the line of feed and at a great distance apart 65 but, of course, it will be understood that the number and arrangement of needles may be changed in accordance with the style of work or width of seam required to be sewed, the loopers, of course, being changed in number 70 and arrangement as will hereinafter be described.

2 represents a drop bar or frame pivoted at one end as shown at 3, and at the other end attached to a rock shaft oscillated from the 75 main driving shaft 4 in the manner referred to in connection with the above mentioned patent. This drop frame or bar in the present instance, is shown as provided with two looper rockers, one behind the other, each 80 carrying a single looper 5 coöperating with a needle 6. Each looper rocker 7 has a separate pitman connection of the ordinary kind with the needle lever of the sewing machine and they are timed to move backward and 85 forward and sidewise in unison.

In Fig. 6, instead of the drop bar or frame 2 upon which the looper rockers 7 are pivoted, a rock shaft *a* is journaled in a bearing *b* on the machine frame and oscillated by means 90 of a fork which embraces an eccentric on the driving shaft 4. This rock shaft *a* has pivoted to it links *c* which at their upper ends are pivoted to a bar *d* operated by the pitman *e* from the needle lever extension and 95 this bar *d* carries the adjustable looper holders *f*. It will be understood, of course, that each rocker might have two or more loopers upon the same, each coöperating with a needle thus increasing the rows of stitches; or 100 any one looper may be arranged to coöperate with two needles arranged side by side, thus, for example, where four loopers are used mounted on two rockers and two needles with each looper, there would be eight 105 rows of stitching upon the top of the goods and four rows beneath. The needles in the needle head carried by the needle bar can be

made adjustable to conform to the adjustment of the loopers. Any suitable arrangement of take up may be used in connection with the looper threads and I have herein shown an old form with the addition of a guiding eye 8 for the thread, but it will be understood that any other form of take up which would suit the purposes may be applied. As a convenient way of securing the looper rockers which are composed of a sleeve 9 with an upwardly projecting arm 10 having a lug 11 in which is secured a ball stud for the attachment of the actuating pinion, which upward extending arm has also a socket for the reception of the looper shank, I have provided a washer 13 which rests against the edge of the drop bar or frame 2 and has an outwardly projecting conical hub upon which the looper rocker fits, the parts being secured together by a screw 14, having a conical head 15 which passes through the drop frame or bar 2 and is secured by a small nut 16 upon the opposite side, the head of the washer 13 being as shown in Fig. 4 riveted to the drop bar or frame, while in Fig. 6 it is secured by set screws, in order to make it adjustable. Of course, the washer may be integral with the drop bar or frame and it may be preferred in practice to construct it that way.

Having thus described my invention, what I claim as new and desire to secure by Letters Patent, is:

1. In a sewing machine, a driving shaft, a frame, a plurality of looper supports pivotally connected to said frame, loopers carried by said supports, said supports being arranged one behind the other in the direction of the length of the loopers, connections between the looper supports and the driving shaft for vibrating said looper supports lengthwise the frame whereby said loopers are moved in the direction of their length,

and means for oscillating the frame carrying the looper supports in a direction transverse to the direction of length of said loopers; substantially as described.

2. In a sewing machine, a driving shaft, a frame or bar, a plurality of looper supports adjustably secured thereto, loopers carried by said supports, said looper supports being arranged one behind the other in the direction of the length of the loopers, and connections between the looper supports and the driving shaft for giving to said loopers vibrating movements in the direction of their length; substantially as described.

3. In a sewing machine, a driving shaft, a frame or bar, a plurality of looper supports adjustably secured thereto, loopers carried by said supports, said looper supports being arranged one behind the other in the direction of the length of the loopers, and connections between the looper supports and the driving shaft for giving to said loopers vibrating movements in the direction of their length, said connections including a single pitman rod connected at one end with the supporting bar or frame, and at the other end with the needle lever; substantially as described.

4. In a sewing machine, a framework comprising a rock shaft, a bar having link connection therewith, and adjustable looper supports on said bar, arranged one behind the other in the direction of the length of the loopers, and means for operating the loopers; substantially as described.

In testimony whereof I affix my signature, in presence of two witnesses.

CHARLES G. KRAMER.
